VACUUM CLEANER CONDUIT

Berry A. Baxter, Altadena, Calif.

Application September 16, 1936, Serial No. 101,047

2 Claims. (Cl. 285—172)

This invention relates to vacuum cleaner conduits.

The general object of my invention is to provide a vacuum cleaner conduit including novelly connected detachable sections.

A more specific object of the invention is to provide a novel detachable connection for a vacuum cleaner conduit.

Another object of the invention is to provide a novel means for connecting a vacuum cleaner conduit to a cleaner body.

An additional object of my invention is to provide novel means for connecting a vacuum cleaner handle to a flexible hose.

Other objects and the advantages of my invention will be apparent from the following description taken in connection with the accompanying drawings wherein:

Fig. 1 is the side elevation of a vacuum cleaner showing my invention attached thereto;

Fig. 2 is a fragmentary sectional view through the closure and conduit;

Fig. 3 is a top plan of the closure;

Fig. 4 is a section taken on line 4—4 of Fig. 2;

Fig. 5 is a detail side elevation showing the securing clamp;

Fig. 6 is a side elevation showing the conduit handle;

Fig. 7 is the fragmentary sectional detail showing the connection between the conduit hose and handle;

Fig. 8 is a section taken on line 8—8 of Fig. 7;

Fig. 9 is a fragmentary elevation showing details of the joint; and

Fig. 10 is a section taken on line 10—10 of Fig. 9.

This application is a continuation-in-part of my co-pending application, Serial No. 58,491, filed January 10, 1936, which matured into Patent No. 2,112,978.

Referring to the drawings by reference characters I have shown my invention as embodied in a vacuum cleaner which is indicated generally at 10. As shown the cleaner includes a housing 11 in which a suitable motor and fan may be mounted.

The upper portion 12 of the housing is provided with an annular ring 14 which is secured in place by means such as bolts 15.

The ring is rabbeted at 16 to receive a flanged collar 17 on which a fabric dirt bag B is mounted.

The ring 14 is provided with a closure 18 which is held in place by securing clamps 19 which are pivoted by screws 20 to the housing. The clamps 19 each include finger engaging portions

21. I preferably provide two clamps 19 and as a third securing member I may provide a clip 22 mounted on the housing and projecting over the top of closure 18. The closure 18 is notched as at 23 to receive the clip and to aid in centering. 5

From the closure 18 an offset conduit 24 extends. This conduit is provided with an enlarged cylindrical skirt portion 25 in which a collar 26 on a cap 27 is arranged. The conduit portion 24 is engaged by a clip 28 similar to clip 22 and 10 which projects through a notch 29 on the cap 27.

The conduit member 24 is provided with a pair of securing members 30 which are shown as connected by screws 31 to bosses 32 and which engage the cap (as shown in Fig. 4) to hold the 15 cap in place. Swivelly mounted in the cap 27, I arrange a tubular member 33 which is flared at its inner end as at 33' to prevent removal but to allow the member to swivel on the cap. The conduit proper at one end comprises a rubber 20 hose 34 which is fitted within the tubular member 33 and secured by cement while the other end of the conduit comprises a metal handle portion which includes a plurality of sections designated 35, 36, and 37 with the section 35 slightly 25 curved. It is to be understood that the number of sections can be varied without departing from the features of my invention.

The end of the handle member adjacent to the hose is connected thereto by a swivel member 38 30 which as shown in Fig. 7 includes an enlarged portion 38' on the end of the tube portion 35 with the enlarged portion having an outstanding flange 39 thereon which is connected to a cylindrical portion 40 which has inwardly directed 35 flange 41 thereon. The hose 34 is cemented in a collar 42 which is flared as at 43 at the end to allow flexibility in the hose.

The collar 42 is provided intermediate its length with a flange 44 which engages the flange 40 40 as shown in Fig. 7. A split spring member 45 is disposed in engagement with the flanges 41 and 44 to thereby allow a swivelling action between the handle and the hose without longitudinal movement between these parts. 45

The section 35 is connected to the section 36 and the section 36 is connected to the section 37, each by a joint 50. Each joint 50 includes an expanded portion 51 which terminates in a bulbous bead 52 and includes an outwardly pressed 50 boss 53 on which a locking lever 54 is pivoted by means of a rivet 55. The locking lever includes a finger engaging portion 56 on one side of the pivot and a hook portion 57 on the other side of the pivot. The hook portion has a slot 55

which is indicated at 58 and which has an undercut face. The bulbous portion 51 is notched as at 60 with the notch so disposed that it is in alignment with the slot when the lever is in one position.

The portion of the section 37 adjacent to the section 36 is provided with a protruding bead 62 against which a gasket 63, which may be an inexpensive rubber band, is fitted and beyond the 10 bead the section 35 is cylindrical as at 64. Beyond the cylindrical portion 64 the length is slightly tapered as at 65 to allow ready assembly. The tapered end 65 is arranged in the direction of flow as indicated by the arrow in Fig. 15 10 so that there is no likelihood of dirt lodging in the joint.

In assembling the parts the locking lever 54 is moved to open position and the lengths are moved to the position shown in Figs. 9 and 10. 20 The locking lever is then swung on its pivot 55 and engages a post 66 on the cylindrical portion 63. The post is fitted within the notch 60 on the bulbous portion 51 and when the lock lever turns this post is engaged between the walls of the slot thus bringing the parts together and compressing the gasket 63.

The lower portion of the forward end of the finger engaging portion 36, as indicated at 67, presses against the adjacent portion of the 30 length 34 and the friction thus developed between these engaging portions serves to hold the parts assembled. Attached to the outer end of the length 37 I show a swivel 70 which may be connected to a suitable nozzle 71. The nozzle, however, forms no part of the present invention and is merely typical of a number of implements which may be secured to the handle portion.

From the foregoing description it will be apparent that I have invented a novel vacuum cleaner conduit which can be readily manufactured and which is highly efficient in use. 40

Having thus described my invention, I claim:

1. In a vacuum cleaner, a conduit, a handle member comprising a plurality of lengths of hollow tubes, said tubes including inner and outer telescoping end portions, said inner end having a bead therein, said outer end having a peripheral outwardly extending bead adjacent to the bead on the inner portion, said outer end having a boss thereon, a locking lever pivoted on said boss, said inner tube having a post thereon, said outer tube having a straight slot in said boss receiving said post, said lever including a hand engaging portion at one end and including a transversally extending notch spaced on the other end of said lever receiving said post. 5

2. In a vacuum cleaner, a conduit, a handle member comprising a plurality of lengths of hollow tubes, said tubes including inner and outer telescoping end portions, the inner end portions including a cylindrical portion and an inwardly 20 tapered extremity, the outer end portions comprising a cylindrical portion, an outwardly tapered portion and a cylindrical extremity on the outwardly tapered portion, said cylindrical portion on the outer end portion being disposed contiguous with the cylindrical portion on the inner portion, said inner end portion having a bead therein, said outer end portion having a peripheral outwardly extending bead adjacent to the bead on the inner portion, said outer end portion having a boss thereon, a locking lever pivoted on said boss, said inner portion having a post thereon, said outer portion bead having a straight slot receiving said post, said lever including a hand engaging portion at one end and including a transversally extending notch spaced on the other end of said lever, said notch receiving said post. 25
